UNITED STATES PATENT OFFICE

BEN J. CHROMY, OF HOPKINS, MINNESOTA, ASSIGNOR TO WIRED RADIO, INC., OF NEW YORK, N. Y., A CORPORATION OF DELAWARE

ELECTRICAL CONTROL SYSTEM

Original application filed May 23, 1929, Serial No. 365,534. Divided and this application filed July 12, 1930. Serial No. 467,602.

This invention relates broadly to electrical apparatus and more specifically to electrically operated illuminating devices of the glow discharge device type.

5 This application is a division of my application, Serial No. 365,534, filed May 23, 1929 for electrical appliances.

An object of this invention is to provide an arrangement for intermittently interrupting and establishing predetermined electrical circuits through glow discharge devices employed in illuminating systems.

10 Another object of this invention is to provide an arrangement for intermittently interrupting and establishing the electrical circuit through successive portions of a glow discharge device unit.

15 Still another object of this invention is to provide an arrangement for rendering successive portions of a glow discharge device illuminating system successively dark.

20 A further object of this invention is to provide an arrangement for intermittently causing different sections of a plurality of adjacent glow discharge devices having different gases therein to glow intermittently.

25 A still further object of my invention is to provide a multiple arrangement of glow discharge tubes connected to an electrical control apparatus for selectively energizing said glow discharge tubes.

30 Other objects and features of this invention will be understood from the specification hereinafter following by reference to the accompanying drawings in which:

35 Figure 1 diagrammatically illustrates one embodiment of my invention; Fig. 2 illustrates a selective control circuit for the system of my invention; Fig. 3 is a cross-sectional view through one form of switching mechanism which may be employed in the apparatus of my invention; Fig. 4 is a perspective view of the switching mechanism illustrated in Fig. 3; Fig. 5 is a fragmentary view illustrating the solenoid mechanism and the means for restoring the armature associated therewith; and Fig. 6 is a fragmentary view of the switch mechanism which is actuated when the armature is 40 shifted to its extreme lower position.

According to this invention a glow discharge device of the type employed in electric signs for advertising or other purposes is caused to flash or flicker in accordance with a predetermined pattern to produce 55 certain desirable and attractive effects.

An electric circuit interrupting mechanism is employed in conjunction with the glow discharge device to connect certain electrodes associated with the glow discharge device into circuit at predetermined intervals whereby sections of the device are periodically energized and de-energized. Through the use of this invention a dark spot or portion may be caused to "travel" 60 along the glow discharge device whereby a moving effect may be produced in the illuminated sign. Other effects in which multi-colored glow discharge devices of the intermittently illuminated variety are employed may be produced by using, for example, a plurality of transparent tubes each filled with a different gas or gases, such as 65 neon, argon, helium, nitrogen, krypton, etc. Gases to which small quantities of readily 70 volatile materials, such as mercury, sodium, potassium, lithium, etc., have been added may also be employed in the glow discharge 75 display devices made in accordance with this invention to produce different pleasing and 80 attractive effects.

Referring to the drawings I have illustrated by reference character 119 a plurality of glow discharge devices each of which is filled with a different gas for producing 85 light rays of a different color. A plurality of transparent tubes 120, 121 and 122 are provided in the glow lamp 119. Each of the tubes 120, 121 and 122 is filled with a different light emitting gas or mixture 90 of gases and readily ionizable materials. Electrodes 120a, 120b, 120c, 120d and 120e are provided in the tube 120; electrodes 121a, 121b, 121c, 121d and 121e are provided in tube 121 and electrodes 122a, 122b, 122c, 95 122d and 122e are provided in tube 122. The electrodes 120a, 121a and 122a are connected to a terminal of the secondary 125 of the transformer 123, the primary 124 of which is energized by the source 126. Taps of 100

selected voltage on the secondary 125 are connected to the segments 135, 136, 137, 138, 139, 140, etc., of the circuit making and breaking device 127. Connections are provided between the segment 129 and the electrode 122b, between the segment 130 and the electrodes 121b and 121c, between the segment 131 and the electrodes 120b, 121c and 122d, between the segment 132 and the electrodes 120c, 121d and 122e, and between the segment 133 and electrodes 120d and 121e, etc.

In operation when the brush or contact arm 128 is caused to establish contact between segments 135 and 129, the portion between electrodes 122a and 122b of tube 122 is caused to glow. When the arm 128 is advanced and contacts with segments 130 and 136 the portions between electrodes 122a and 122c and between electrodes 121a and 121b of tubes 122 and 121 respectively are caused to glow and as the arm 128 is advanced to segments 131 and 137 the portions between electrodes 122a and 122d, between electrodes 121a and 121c and between electrodes 120a and 120b of tubes 122, 121 and 120, respectively are caused to glow. This operation is advanced until the whole glow lamp 119 is emitting light when the lamp is caused to become dark and the operation repeated. The lamp becomes dark when the arm 128 of the circuit making and breaking device 127 is out of connection with contact segments 135—140 and 129—134, etc. and prior to the commencement of the succeeding cycle when the arm 128 of the circuit making and breaking device again establishes connection with the successive contact segments. The tube 122 is filled with a gas that is more readily ionizable than the gases used in tubes 121 and 120.

The switching arrangement 127 may be made up of two discs having a plurality of segments over which arm 128 is periodically driven as shown in Figs. 3 and 4 or it may be in the form of a relay system such as illustrated in Fig. 2. Fig. 3 is a side elevational view with parts shown partially in cross-section and illustrating one arrangement of the switching mechanism illustrated in Fig. 1. The mechanism shown is to be considered entirely in the illustrative sense and not in a limited sense. In the form of the switching mechanism shown, the motor 172 which is supported with respect to base 173 as illustrated, is arranged to drive rotatable shaft 174 journaled in bearings 175. Shaft 174 has a radially extending insulated member 176 thereon which carries the conductive arm 128. The arm 128 as heretofore described provides a shunt path between sets of contacts 135—140 and 129—134. The contacts are carried by insulated discs 177 and 178 supported with

respect to base 173, between which arm 128 moves. The arrangement of the mechanism is shown more clearly in Fig. 4 from which it will be observed that conductive arm 128 passes periodically over the sets of contact segments and passes over sets of contact segments which are left electrically free. During this latter portion of the travel of conductive arm 128, the lamp is dark.

Where the relay system illustrated in Fig. 2 is employed to operate the display system illustrated in Fig. 1, the contacts 159 are connected to correspond to the segments 129 and 135, contacts 160 to correspond to segments 130 and 136 etc. A source of current supply 153 is connected to each of the sections 142, 143, 144, 145 and 146 of the solenoid 141. Connections are also provided between the contacts 154, 155, 156, 157 and 158 and the sections of the solenoid. A piston 152 operating in cylinder 151 is connected to the armature 147 so that more uniform operation of the relay is obtained. The piston and cylinder arrangement is also employed to return the armature 147 to its open circuit position with the aid of spring 170 which normally tends to raise armature 147 in its extreme upper position. A contactor 149, of metallic material, such as copper or brass, is mounted upon the rod 148 which is of insulating material. A second contactor 150 also of metallic material is mounted upon the contactor 149. The contactor 150 is insulated from the contactor 149.

In operation the section 142 of the solenoid 141 is energized and the plunger of the armature 147 is caused to be pulled into the center of the section 142 whereupon the contactor 150 engages the contact 155 and the section 143 is energized. The armature 147 is drawn further into the solenoid 141 and the contactor 149 is caused to engage the contacts 160 while the contactor 150 closes the circuit between the source of current supply 153 and the section 144. This operation is continued until the armature is drawn all the way down into the solenoid 141 as shown more clearly in Fig. 6, at which time the piston 152 engages a member 164 which is of insulating material connected to arm 165a and opens the circuit of the source of current supply 153 and the section 146 of the solenoid 141 at contacts 165 by movement of arm 165a against the action of spring 171. The armature 147 is then returned to its original starting position by aid of spring 170 shown more clearly in Fig. 5 and the contactor 149 engages the member 164 and the circuit between the source of current supply 153 and the solenoid 141 is established through the contacts 165.

It is, of course, apparent that the piston and cylinder arrangement 151 and 152 may be replaced by a spring of the proper ten-

sion or by a gravity operated mechanism. Compensation is also necessarily provided for the increased pull upon the armature because of the increased pressure upon the piston 152 as the armature is drawn further into the solenoid; this may be done by progressively increasing the number of turns on the sections 142, 143, 144, 145 and 146 of the solenoid 141.

10 It will be observed that various modifications of this invention may be made without departing from the spirit and scope thereof and that, therefore, I do not desire to limit this invention to the exact details as set forth

15 in the foregoing specification except in so far as they are defined by the appended claims. What I claim as new and desire to secure by Letters Patent of the United States is as follows:

20 1. In systems of the class described, the combination of a plurality of glow discharge devices each having different color emission characteristics positioned adjacent to each other in different parallel paths, each of

25 said glow discharge devices containing a gaseous medium having a different ionizing potential, a source of current supply for selectively ionizing the gaseous medium in each of said glow discharge devices, means

30 for interrupting and establishing the circuit between selected sections of each of said glow discharge devices and said source of current supply, in predetermined order, and means for impressing different potentials

35 across the different sections of said glow discharge devices.

2. In a visual display system, a multiplicity of parallel extending tubes of transparent material, a plurality of glow discharge

40 electrodes positioned at spaced intervals in each of said tubes, gases of different color characteristics saturating said tubes, and means for applying different potentials across separate sets of said electrodes in each

45 of said parallel extending tubes for producing ionizing effects in predetermined order in differing parts of said tubes for producing a predetermined composite color effect for effecting a visual display according to a particular pattern.

3. In a visual display system, a transparent envelop divided into a plurality of longitudinally extending chambers, a multiplicity of glow discharge electrodes disposed at

55 spaced intervals along each of said chambers, said chambers each containing gases of different color characteristics and means for selectively energizing selected sets of said electrodes in different parts of said chambers

60 with different ionizing potentials for effecting discharge in differing parts of said parallel extending chambers in predetermined order for producing a composite color effect according to a prearranged pattern.

65 4. In systems of the class described, the

combination of a plurality of glow discharge devices positioned adjacent to each other in immediately adjacent parallel paths, a multiplicity of separate electrodes disposed at spaced intervals in each of said devices, means for energizing selected sets of the electrodes in said glow discharge devices in accordance with a predetermined pattern, separate sections of said glow discharge devices being energized at different potentials, and a gas of different color characteristics in each of said glow discharge devices for combining the discharge effects of all of said devices.

In testimony whereof I affix my signature. 80
BEN J. CHROMY.
